ATTORNEYS

UNITED STATES PATENT OFFICE.

LILIAN MAY ELLIOT, OF NEW YORK, N. Y.

SAND-BOARD.

SPECIFICATION forming part of Letters Patent No. 605,198, dated June 7, 1898.

Application filed May 27, 1897. Serial No. 638,344. (No model.)

To all whom it may concern:

Be it known that I, LILIAN MAY ELLIOT, a citizen of the United States, and a resident of New York city, county of New York, and 5 State of New York, have invented certain new and useful Improvements in Sand-Boards, of which the following is a specification, reference being had to the accompanying drawings, forming a part thereof, in which similar letters and figures of reference indicate corresponding parts.

This invention relates to improvements in sand-boards for educational purposes; and the object thereof is to provide a device of 15 this character which is so constructed as to be maintained normally in a suspended position against the wall, whereby but little space is required when the device is not in use, while at the same time it is susceptible of being 20 instantaneously and easily adjusted into operative position when required.

The device is simple in construction, inexpensive, and durable, and it is so constructed that the sand may be constantly contained 25 therein without danger of spilling, whereby the necessity of removing the sand from the board is obviated.

The invention will be hereinafter fully described, and specifically set forth in the annexed claim.

In the accompanying drawings, forming 30 part of this specification, Figure 1 is a perspective view of my improved sand-board, illustrating the same in its open or operative position; and Fig. 2 is a vertical sectional elevation thereof, showing the board suspended in its normal position against the wall.

In the practice of my invention I provide, primarily, an ordinary sand-board A. This 40 said board comprises a backing or base a and a surrounding flange a', the said flange being extended some distance beyond the face of the backing for the purpose of supplying a receptacle to receive the sand. This board 45 is preferably of rectangular contour, and secured to the rear edge thereof are two metallic straps B. These said straps are looped into similar straps C, adapted for attachment to the wall D by means of screws c, whereby 50 the board is normally suspended against the wall, as illustrated in Fig. 2 of the drawings. The board also contains a small receptacle a²

in one corner thereof for the reception of chalk or crayons.

Upon the top edge of the flange or rim a' 55 I place a rubber or other flexible binding E, and to the rear edge of the board a cover F is hinged. This said cover comprises a frame f and a slab f', composed of slate or other substance adapted for use as a blackboard 60 and having both sides finished, whereby it can be used as a means for illustration either when the board is in an open or a closed position. This said cover is normally held in a closed position by means of a spring-clamp 65 G, whereby the sand contained within the receptacle will not escape when the cover is closed, and the pressure exerted against the flexible binding E will maintain a tight joint around the edge of the receptacle. 70

As a means for supporting the board when it is in an open or operative position, as illustrated in Fig. 1 of the drawings, I provide swinging brackets H. These brackets comprise members h and h', hinged to each other 75 at their point of juncture, the member h being secured to the wall by means of screws h², the member h' being supplied at its upper edge with an extended flange h³, upon which the board is supported while the sand is being manipulated. 80

When the board is not in use, the members h' of the brackets H are folded against the wall, the board being suspended between the brackets in a closed position, as illustrated 85 in Fig. 2, whereby but little space is taken up, while at the same time a blackboard is constantly presented for use.

The necessity of a device of this character will be obvious to teachers and others familiar 90 with present educational methods.

In use, the board will contain a quantity of sand, and the face of the backing a will be painted blue. This blue surface represents water, and the sand represents land, and in 95 using the device the instructor forms the sand into the shape of a map, whereby the study of geography is made very interesting for small children.

Having thus described my invention, what 100 I claim as new, and desire to secure by Letters Patent, is—

As an educational device, a sand-board A, adapted to contain sand and provided with

a backing a , a surrounding flange a' extended from the backing, straps B secured to the rear edge, straps B adapted to be looped into straps C and attached to the wall, a receptacle a^2 , a flexible binding E on said flange, adapted to prevent the escape of the sand, a cover, F, hinged to said board and means for supporting the board, comprising swinging brackets, H, attached to a support and adapted to permit the device to rest between

them against the wall, substantially as shown and described.

In testimony that I claim the foregoing as my invention I have signed my name, in presence of two witnesses, this 22d day of May, 1897.

LILIAN MAY ELLIOT.
